Ralph Epstein, New York, N. Y., assignor to Jacques Kreisler Manufacturing Corporation,
North Bergen, N. J.

Application December 13, 1946, Serial No. 135,487

Term of patent 7 years

(Cl. D80—9)

To all whom it may concern:

Be it known that I, Ralph Epstein, a citizen of the United States of America, residing at Bronx, New York, New York, have invented a new, original, and ornamental Design for a Combined Display Stand and Card or Similar Article, of which the following is a specification, reference being had to the accompanying drawing, forming a part thereof.

Figure 1 is a perspective view of a combined display stand and card or similar article, showing my new design.

Fig. 2 is a side view thereof.

Fig. 3 is a top plan view thereof.

The dominant features of my design reside in the portion shown in full lines.

I claim:

The ornamental design for a combined display stand and card or similar article, as shown and described.

RALPH EPSTEIN.
